UNITED STATES PATENT OFFICE.

FRED A. REARDON, OF BRIDGEPORT, CONNECTICUT, ASSIGNOR TO HAMEL SHOE MACHINERY COMPANY, OF BRIDGEPORT, CONNECTICUT, A CORPORATION OF MASSACHUSETTS.

NAILING MACHINE.

Application filed November 10, 1920. Serial No. 422,985.

To all whom it may concern:

Be it known that I, FRED A. REARDON, a citizen of the United States, residing at Bridgeport, in the county of Fairfield and

- 5 State of Connecticut, have invented certain new and useful Improvements in Nailing Machines, of which the following is a specification, reference being had therein to the accompanying drawings.
- 10 This invention relates to nailing machines being particularly intended for nailing heels on shoes where the nails are driven from within the shoe. For this purpose a shoe jack, having at its upper end a last member 15 insertable within the heel portion of a shoe and engaging the sole with its upper face, is slidably supported on the machine frame. This last member is made as a nail block having a plurality of nail tubes therein and 20 a gang of reciprocating nail drivers are slideable within the tubes. These drivers have an extension down through the jack, which, on sliding of the jack to one limit of its path is placed in line with a driver actuator 25 carried by the machine. At the other limit of its path the jack is out of alignment with the actuator, while the nail block, which is not at that time carrying a shoe, is in cooperative relation to a nail loading device by 30 which a nail is fed head downward into each nail tube and is supported by the end of the driver therein. It sometimes happens with such a construction, through faulty operation of the nail loader, that one 35 or more nail tubes will fail to receive a nail.

One feature of this invention relates to means by which the failure of the nail tube to receive its nail will be readily observed by the operator in advance of the driving operation so that a nail may be supplied, to insure the heel being properly nailed on the driving stroke. This is effected in the present invention by providing a stop to limit the retraction of the drivers so that the 45 points of the nails in the tubes are adjacent the upper ends thereof where they may be readily seen on movement of the jack to driving position so that the absence of a nail is readily noticed. This stop is made 50 adjustable for nails of different lengths.

A further feature of this invention relates to a counter-engaging element carried by the nail block and adjustable thereon to determine the position of the nails longitudinally of the shoe. This adjustment is de-

sirable to properly position the nails for variously shaped heels to avoid splitting the latter by driving nails into the weaker portions thereof.

For a more complete understanding of this invention together with further objects and advantageous details and combinations of parts reference may be had to a description of an embodiment thereof disclosed in the accompanying drawings in which,

Fig. 1, represents a fragmentary view partly in section of the jack supported on the machine in nail driving position with the nails in position to be driven.

Fig. 2, is a somewhat similar view showing the nails as driven into the heel, and,

Fig. 3, is a section through the nail block on line 3—3 of Fig. 1.

In these drawings A represents a portion of the machine frame having a slideway 1 at its upper face. Mounted to slide in this way is a jack indicated at B. At its upper end the jack B carries a last member comprising a nail block 2 having a plurality of nail tubes 3 vertically arranged therein. The nail block is made fast by means such as screws 4 to upstanding arms 5 and 6 at the top of the jack B. Slidably mounted in the nail tubes 3 is a gang of nail drivers each driver being indicated by 7, the lower ends of these drivers terminating in a plate 8 to which they are made fast. The jack B has a vertical perforation in which is slidably mounted a rod 9 which is fastened to the plate 8 by a screw 10 passing therethrough, and threaded on the end of the rod 9 near the base of the jack B and mounted to slide in an enlarged recess 11 therein is a block 12. This block has a slot 13 in the side thereof, and a key 14 carried in a similar slot 15 of the recess 11 engages in the slot 13, this key being fixed in position by a bolt 16. By this means block 12 is prevented from rotation within the recess 11. The lower end of rod 9 is threaded into the block 12 at 18 and the upper end of rod 9 has a series of holes 19 therein for the reception of a tool by which rod 9 may be rotated to adjust the vertical position of the block 12 relative thereto.

Thus, not only is the amplitude of operative movement of the thrust-rod 9 determined, and hence the advance positions of the drivers, through the adjustment of the block 12 upon said rod, but the initial posi-

tions of the points of the nails within the tubes 3 are fixed by adjustment of the positions of the drivers by means of the stop-screw 28. In other words, the adjusting means 28 determines the initial or retracted positions of said drivers and the adjusting means 18 determines their advance positions, so that provision is made for adapting the machine for applying nails of different lengths to heels of different heights.

The jack is provided with a handle 20 and a latch pin 21 passing through the lower portion thereof is arranged to engage in perforations, one of which is shown at 22, in the frame A to lock the jack at either limit of its sliding motion. The latch pin 21 has a laterally extending pin 21' which projects through the forked extremity of a lever 23, this lever having an upwardly extending actuating arm 24, normally urged away from the handle 20 by means of a coil spring 25, the action of this spring serving to urge the latch rod 21 into latching position, and the arm 24 being engageable by the operator's fingers to release the locking bolt when desired.

At one end of the slideway 1, frame A has a downwardly extending portion 26 within which a driver actuator member 27 is reciprocable. When the jack is in the position shown in Fig. 1, the driver actuator is in alignment with the rod 9 and on upward movement thereof impinges against the block 12 and imparts the nail driving stroke to the drivers 7. The actuator 27 on its retraction passes below the surface of the frame A so as not to interfere with the sliding motion of the jack B. It is preferably given a stroke of constant amplitude as by means of a crank, the final driving position of the drivers 7 being adjustable by regulating the position of the block 12 on the rod 9. Immediately below the plate 8 an adjusting screw 28 is threaded into the top face of the jack B, this screw having a head provided with perforations 29 for the reception of a tool by which the screw may be turned to adjust its height, the screw forming a stop for limiting the downward movement of the drivers.

The rear face of the block 2 has a slot cut therein substantially parallel to its upper face at 30 and slidably mounted therein is a counter-engaging member 31. This member has a pair of forwardly projecting pins 32 and 33 projecting within the mating perforations 34 and 35 in the block 2. A screw 36 passing through one wall of the block 2 engages the pin 33 to lock the block 31 in adjusted position.

The operation of this mechanism is as follows:—

The parts being in the position shown in Fig. 1 except that the nail tubes have no nails therein, the operator grasps the han-

dle 20 and by movement of the arm 24 releases the bolt 21 and then pushes jack B rearwardly along the slideway into co-operation with a suitable nail loading mechanism by which nails are fed into the nail tubes 3 head downwardly, the heads resting on the ends of the drivers 7. The operator then pulls forwardly on the handle 20 bringing the jack B again in position shown in Fig. 1 with the rod 9 in alignment with the actuator 27. By turning the screw 28 the position of the drivers may be adjusted so that the points of the nails may be readily visible at the upper ends of the nail tubes. When so adjusted it is evident that should the nail loader fail to fill one of the tubes, on retraction of the jack from the loader, this failure is readily apparent to the operator who may place a nail in position in the vacant tube. The shoe is then placed in position over the nail block as shown in Fig. 2, the member 31 engaging the counter and being adjusted so as to position the nails in the desired relation lengthwise of the shoe so that they may enter into the stronger parts of the heel on the operation of the machine. By mounting the counter engaging member in a slot as shown, all danger of the upper being caught between it and the block is obviated. Actuator 27 is then moved upwardly, contacting with the block 12, and raises the same together with the rod 9 and the drivers to impart the driving stroke to the latter. On retraction of the actuator 27 into the position shown in Fig. 1, the machine automatically stops and the nail drivers 7 retract until the plate 8 impinges on the head of the screw 28. The shoe is then removed and the parts are then in position for repetition of the same cycle of operation.

Having thus described one embodiment of this invention it should be evident that many changes and modifications might be made therein without departing from its spirit or scope as defined by the appended claims.

1. In combination, a nail-block having a plurality of nail-tubes therein, a gang of nail-drivers disposed within said tubes to support and drive nails placed therein, a nail-driver actuator member adapted to impart to said nail-drivers operative nail-driving strokes having a predetermined limit of advance movement, and means for adjustably determining the retracted nail-supporting position of said drivers independently of said limit of advance movement thereof.

2. In combination, a nail-block having a plurality of nail-tubes therein, a gang of nail-drivers disposed within said tubes to support and drive nails placed therein, a nail-driver actuator member adapted to impart operative nail-driving strokes to

said nail-drivers, means for adjustably determining the limit of effective advance movement of said actuator-member, and means for adjustably determining the retracted position of said drivers irrespective of said effective advance movement of the driver actuator member.

3. In a heel nailing machine, a nail block movable from nail loading to nail driving position and having a plurality of nail tubes, a gang of nail drivers reciprocable in said tubes to drive nails supported on said drivers in said tubes, an actuator movable in a fixed path and engageable with said 10 gang for imparting thereto nail driving movement when said block is in driving position, and means for adjustably deter-

mining the limit of retractive movement of said drivers independently of said actuator.

20

4. In a shoe-heel attaching machine, a frame provided with a slideway, a jack fitted to and laterally movable within said slideway, means for locking said jack in nail-driving and in retracted positions, a 25 nail-block sustained by said jack and provided with a plurality of nail-driver tubes, nail-drivers within said tubes, and means sustained independently of said jack and positioned to actuate said drivers when the 30 jack is in nail-driving position.

In testimony whereof, I have signed my name to this specification.

FRED A. REARDON.
